UNITED STATES PATENT OFFICE

JAMES H. DEAN, OF LUDINGTON, MICHIGAN, ASSIGNOR TO JAMES W. PEARCE, OF
PHILADELPHIA, PENNSYLVANIA

FABRICATED METAL STRUCTURAL MEMBER

Application filed June 16, 1930. Serial No. 461,326.

This invention relates to improvements in fabricated metal structural members and it consists of the matter hereinafter described and more particularly pointed out in the appended claims.

6 Pending claim. The primary object of the invention is to provide a structural member that can be fabricated from a strip of metal of desired cross sectional shape, which member is adaptable for many uses, such as studding or as a reinforcing bar in concrete, the latter use, of course, calling for a member of greater cross sectional dimensions but in all other respects embodying all the essential features 10 of the invention.

Another object of the invention is to provide a member of this kind having longitudinal spaced integral arched trusses or strands along its margins, produced by slitting and deforming portions thereof out of their normal plane, with the trusses or strands of one margin staggered or offset with respect to those of the other margin, whereby a transverse strain at any point along the member is amply resisted by a truss or strand.

Another object of the invention is to provide a member of this kind, which may be readily made at a cost competitive with other members now made for a similar purpose, and when so made even from light gage metal is exceedingly strong and rigid and is indeed efficient for the many purposes to which it can be put.

35 These objects of the invention as well as others, together with the advantages thereof, will more fully appear as I proceed with my specification.

In the drawings:—

40 Fig. 1 is a perspective view of a short piece of a fabricated structural member of H-beam cross section and constituting the preferred form of the invention.

Fig. 2 is a view in side elevation of the
45 same.

Fig. 3 is a view in front elevation of the same.

Fig. 4 is a detail view in elevation showing the member illustrated in Fig. 1 as being used as a retaining element for wall

board and the like, with respect to the associated studding upon which said wall board is to be supported.

Fig. 5 is a horizontal detail sectional view as taken on the line 5—5 of Fig. 4, after a coating of plaster has been applied. 55

Fig. 6 is a detail sectional view as taken on the line 6-6 of Fig. 5 showing the manner in which those portions of the member embedded in the plaster, form keys therein and materially reinforces the plaster at this place.

Fig. 7 is a detail sectional view showing a member similar to that of Fig. 1 when used in a reinforcing bar in concrete work. 65

Fig. 8 is a transverse section as taken on the line 8-8 of Fig. 7.

Fig. 9 is a detail view showing a modified form of the invention, having a T-bar cross section. 70

Fig. 10 is a view in side elevation of a further modified form of the invention having a channel bar cross section.

Fig. 11 is a transverse sectional view through the member of Fig. 10 as taken on the line 11-11 thereof. 75

Referring now in detail to that embodiment of the invention illustrated in Figs. 1 to

3 inclusive of the accompanying drawings:—
1 indicates as a whole a structural member embodying my invention which is generally of an H-bar or beam cross section. Said member is made or fabricated from a strip of flat stock of the desired gage and width and longitudinally spaced portions of each margin thereof are simultaneously slit and deformed out of the plane of the mid portion or web 2 to form a plurality of longitudinally spaced arched trusses or strands 3 and 4 respectively, connected at their ends to the web by bonding portions 5. In the fabrication of the member, those portions of the strip which are deformed to provide the trusses or strands are materially stretched and are therefore put under tension whereby they become extremely rigid. In this respect it is pointed out that generally the width of the strands will approximate the thickness of the strip from which the member is formed so

that each strand will be substantially square in cross section.

Of course, the disposition of the arched trusses or strands has quite a bearing upon the stiffness and rigidity of the finished member and in practice I find it best to form the alternate trusses and strands of one margin, upon one side of the member and to form the intermediate ones upon the other side of

- 10 the member. Furthermore, I find it best to stagger or offset the trusses of one margin with respect to those of the other margins as best illustrated in Figs. 2 and 3 whereby any transverse strain imposed at any point along 15 the member is resisted or interrupted by at least one truss or strand.

As shown in the drawings, each bonding portion 5 in one margin of the member is arranged opposite an end portion of the truss

- 20 or strand in the other margin of said member. If desired, this arrangement may be changed to bring the bonds in one margin directly and centrally opposite the trusses or strands in the other margin, without departing from the 25 spirit of the invention. However, it is pointed out that it is not desired to so arrange said trusses or strands as to bring the bonding portions in one margin of the member opposite those in the other margin because 30 this arrangement would permit bending of the member in the plane of said bonding portions and could materially decrease the rigidity and strength of the member as a whole.

- In Fig. 4, I have illustrated a member such 35 as above described, employed as a means by which sheets of wall board or the like 6 are secured in place to studding 7. In the use of the structural member for this purpose, the vertical margins of the adjacent sheets are 40 disposed, in the grooves as defined by the trusses or strands 3 and 4 on both sides of the web 2, the said margins having edge engagement with the web and snugly fitting between the trusses or strands so as to be held 45 in the same plane and against any bulging. Staples 8 are arranged to straddle the web and are driven through the wall board sheets into the studding 7. In practice with $3\frac{1}{2}$ " wall board sheets, the transverse distance be- 50 tween the trusses or strands on both sides of the web will approximate that measurement but this measurement of course, can be varied to suit the particular thickness of wall board sheet with which the members are to be used. 55 To secure the horizontal margins of adjacent sheets together, I employ shorter pieces 1^a of such a member and as before described the trusses or strands thereof engage opposite sides of said sheet margins whereby they are 60 held against springing or bulging so that a good even surface is obtained. Of course, the exposed surface of the wall board sheets are covered with a coating 9 of plaster and this encloses the trusses or strands of the 65 said member arranged on that surface of the

sheet. Thus those parts of the plaster within the trusses or strands form keys 9^a as best shown in Fig. 6 and this taken in connection with the fact that the strands along that margin of the member enclosed in the plaster, zig 70 zag back and forth across the joint between the wall sheets provides a joint that is materially reinforced so that cracking of the plaster along this line is greatly reduced if not entirely eliminated. It is also pointed 75 out that instead of employing staples for the purpose described, ordinary headed lath nails may be substituted therefor with good results.

In Figs. 7 and 8, I have shown a member 80 1^b as used as a reinforcing bar in a mass of concrete 10. When so used, it is of course, understood that the member is made of heavier stock and will have truss members of greater length and height. Preferably the 85 members when used as horizontal reinforcing bars in concrete will be disposed with the web arranged in a perpendicular plane. This will insure a complete inclosing of the said member and with no voids as the finer portions of the concrete will effectively pass through the openings as defined by the trusses and completely fill the same. Such a member where used as a reinforcing bar in concrete 90 will materially strengthen the same with a 95 considerable saving of weight in the reinforced structure. In other words, with my improved member used as a reinforcing bar, less metal for the same strength desired is attained.

In Fig. 9, I have illustrated the invention as embodied in a structural member having the well known T-shaped cross section. 1^c indicates the member as a whole which includes a web or strip 11, one marginal portion of which is deformed from opposite sides to provide the trusses or strands 12. When such a structure is used in connection with the wall board sheets 6 the free edge of the web is engaged with the studding 7 and the margins of the wall board sheets 6 are engaged between the studding and said trusses or strands. When plaster is applied to that side of the wall board sheets engaged by the trusses or strands, that portion of the plaster filling in the spaces within the trusses form keys in the plaster for the purpose well known. Such a member, of course, will leave the rear surface of wall board sheets in engagement with the studdings, instead of being spaced from the same as occurs in connection with the member shown in Fig. 5.

Figs. 10 and 11 show another modified form of the invention wherein the member 1^d therein takes on a C-channel shape cross section. Such a member comprises a web 13 and the trusses or strands 14 are deformed from both margins of said web upon the same side thereof. Such a member which is especially adapted as a "runner" bar for starting parti- 120 125 130

tion and ceiling work, has the trusses or strands staggered to rigidify the same as a whole as before.

The members described are especially adapted for use in partition made of wall board in sheet form and have advantages over the conventional H and Z type of channels now used because, said members embody less metal without a sacrifice in strength and 10 rigidity and no metallic fabric reinforcing strip is required in the plaster covering the joint between adjacent sheets.

While in describing the invention, I have referred in detail to the form, arrangement 15 and construction of the member embodying my invention, the same is to be considered as illustrative only so that I do not wish to be limited thereto except as may be specifically set forth in the appended claims.

20 I claim as my invention:—

1. A structural member of the kind described embodying therein a web and arched strands connected at their ends to each margin of the web with their arched portions 25 extending in a plane at right angles from the wide surface planes of said web and the strands of one margin being offset longitudinally of the web with respect to those of the other margin.

30 2. A structural member of the kind described embodying therein a web and arched strands formed integrally from each margin of the web with their arched portions extending in a plane at right angles from the wide surface planes of said web and with the strands of one margin offset longitudinally of the web with respect to those of the other margins.

35 3. A structural member of the kind described embodying therein a web and arched truss like strands stretched in directions perpendicular to the wide surface planes of the web and formed integrally from each margin of the web.

40 4. A structural member of the kind described embodying therein a web and truss like strands formed integrally from each margin of the web, with the strands of one margin offset longitudinally of the web with 45 respect to those of the other margin, each strand being stretched to arch shape at right angles to the face of the web.

45 5. A structural member of the kind described embodying therein a web having integral strands extending from both margins 50 of the web in planes at substantially right angles to the plane of the web face, with the strands of one margin offset longitudinally of the web with respect to those of the other 55 margin.

60 6. A structural member of the kind described embodying therein a web having integral strands stretched from both margins 65 of the web in planes at substantially right angles to the plane of the web face, with the

strands of one margin offset longitudinally of the web with respect to those of the other margin.

7. A structural member of the kind described comprising a web and arched truss like strands connected to both margins of the web apices of the arches projecting at substantially right angles from both sides thereof, the strands of one margin projecting alternately from both sides of the web and being offset longitudinally of the web with respect to those of the other margin. 75

8. A structural member of the kind described comprising a web and integral truss like strands extending at substantially right angles from both margins of the web and projecting from both sides thereof, the strands of one margin projecting alternately from both sides of the web and being offset longitudinally of the web with respect to those of the other margin, all of said strands being stretched strands and under tension. 85

9. A structural member of the kind described comprising a strip of sheet metal the margins of which are cut at intervals and stretched into arched strand trusses projecting from opposite sides of the strip at substantially right angles to impart to the member the properties that would be imparted by a substantially H-shaped cross section. 95

10. A structural member of the kind described comprising a strip of sheet metal having portions of its margins slit at intervals, and marginal cut portions, stretched and expanded in a direction at right angles to the surface of the sheet metal to provide a channel on each side of the member so as to impart to said member the properties of a member having a substantially H-shaped cross section. 100

105 In testimony whereof, I have hereunto set my hand, this 7th day of June, 1930.
